[57] CLAIM

The ornamental design for an immunoassay tray, as shown and described.

DESCRIPTION

FIG. 1 is a top, rear perspective view of an immunoassay tray showing our new design;

FIG. 2 is a bottom, front perspective view thereof;

FIG. 3 is a top, rear perspective view of a second embodiment thereof;

FIG. 4 is a bottom, front perspective view thereof;

FIG. 5 is a side view of the first embodiment thereof, the opposite side being a mirror image; and

FIG. 6 is a side view of the second embodiment thereof, the opposite side being a mirror image.

Some cylinders have not been shown. The illustrated cylinders are identical and are arrayed across the entire tray in the manner illustrated by the broken lines.

FIG. 1

FIG. 2

FIG. 3

FIG. 4

FIG. 5

FIG. 6
